UNITED STATES PATENT OFFICE.

HENRY W. PUTNAM, OF CLEVELAND, OHIO.

IMPROVED CLOTHES-WRINGING MACHINE.

Specification forming part of Letters Patent No. 36,728, dated October 21, 1862.

To all whom it may concern:

Be it known that I, HENRY W. PUTNAM, of Cleveland, in the county of Cuyahoga and State of Ohio, have invented new and useful Improvements in Wringing Machines, the same being an improvement upon a patent granted to me under date of December 17, 1861; and I do hereby declare that the following is a full and complete description of the construction and operation of the same, reference being had to the accompanying drawings, making part of this specification, in which—

Figure 1 is a perspective view. Fig. 2 is a sectional view of one of the side pieces and rollers. Fig. 3 is a perspective view of one of the side pieces, and Fig. 4 is a cross-section of the same in the direction of the line $x' x'$ in Fig. 2.

Like letters refer to like parts.

My improvement relates to the general form and structure of the side pieces, and to the manner of securing the same to the tub.

The side pieces, A B C, as a whole, are duplicates of each other, only in their construction they are reversed, being formed in pairs, or right and left. Both are provided with a segmental ratchet, D, pawl E, and cam F, by means of which the machine is secured to the tub.

The side pieces are made of cast-iron, and galvanized or coated with zinc or other metal that will preserve the iron from corroding.

The upper section, A, consists of a barrel, in which is placed a coiled spring for pressing the rollers together. The upper end of this spring rests against the under side of the cross-bar G, which is secured to the upper end of the barrel A by means of a slot and mortise, (seen at H, Figs. 2 and 3.) At the lower end of the barrel A is another slot, upon the inside, as seen at H', to allow an upward movement of the upper roller in the working of the machine.

I I' represent flanges or lips, which cover the ends of the rollers both in front and rear, for about half an inch, to prevent the clothes from getting foul around the ends thereof. By this means the clothes can be run through from either direction without working out from between the rollers. In this way, by placing another tub close by the side of the

one to which the machine is fastened, it can be made to perform the office of a washing-machine, by passing the clothes frequently back and forth between the rollers.

The piece B projects forward and downward, as seen in the figure, fitting the inside of the tub, extending down some five or six inches. From the top of the piece B the piece C projects outward and downward, leaving a space between B and C of sufficient width to admit the thickness of the staves of the tub. The parts B and C thus bifurcate, one arm being inside and the other outside, of the tub. To the outside arm is secured the segmental ratchet D. It may be riveted on or cast with it. I prefer the latter. The pawl E and cam F (constituting one piece) is attached by means of the rod G', or otherwise. The method shown in the drawings is the most economical and substantial.

The rollers K are made, as usual, of vulcanized india-rubber, upon iron shafts, and the lower one is turned by a crank, L.

When the machine is placed upon the tub, with the pawl E up, the cam will rest lightly against the outside of the tub. Now, by pressing the pawl downward, the cam presses with an increasing pressure against the tub, securing the machine firmly thereto. The tooth upon the pawl-handle fits into one or another of the ratchet-teeth and holds it fast. A lever may be used for the same purpose, with notches upon its upper surface, into which the pawl may fit; but this I consider an equivalent to the method I have herein described.

In the construction of the flanges or lips I I' they may be made straight, as shown in the drawings, or they may be curved inward between the rollers, and carried around them, both above and below, in such a manner that the lips I and I' may nearly or quite meet at their respective ends.

The section A or barrel of the side pieces may be removed, and the spring so arranged as to operate on the rollers from below, substantially as above, or the spring in the barrel may be connected with either of the sections B C, and attached by suitable means to one end of a lever, the opposite end being pivoted to the side piece, so that the lever will be pressed down upon the bearings of the rollers, the bearings forming fulcrums for the

levers; but I prefer the manner hereinbefore described.

What I claim as my improvement, and desire to secure by Letters Patent, is—

The side pieces constructed in pairs, and consisting of the parts A B C, ratchet D, cam E, and pawl F, in combination with the flanges

or lips I, I', arranged as and for the purpose specified.

H. W. PUTNAM.
